UNITED STATES PATENT OFFICE.

HIERO GILLAS TIFFANY, OF ST. LOUIS, MISSOURI.

STAND.

1,426,327.

Specification of Letters Patent. Patented Aug. 15, 1922.

Application filed October 4, 1920. Serial No. 414,585.

To all whom it may concern:

Be it known that I, HIERO GILLAS TIFFANY, a citizen of the United States, residing at St. Louis, Missouri, have invented a certain 5 new and useful Improvement in Stands, of which the following is a full, clear, and exact description, such as will enable others skilled in the art to which it appertains to make and use the same.

10 This invention relates to stands of the kind that are equipped with rollers or casters for facilitating the movement of the stand from one place to another, and also provided with means for raising the rollers out of contact with the floor on which the stand rests when it is desired to support the stand rigidly in a stationary position.

One object of my invention is to provide an efficient stand of the general type referred 20 to, which is of such design that there are no portions at the lower ends of the legs which form lateral projections on which a person is apt to trip when passing the stand.

Another object is to provide a stand of the 25 general type referred to whose raising and lowering mechanism is adapted to be operated by the user's foot.

And still another object is to provide a stand raising and lowering mechanism of 30 rugged construction that is inexpensive to manufacture and easy to apply. Other objects and desirable features of my invention will be hereinafter pointed out.

Figure 1 of the drawings is a perspective 35 view of a stand constructed in accordance with my invention.

Figure 2 is an enlarged vertical sectional view of the lower end portion of one of the legs.

40 Figure 3 is a cross sectional view of one of the rock shafts that forms part of the raising and lowering mechanism.

Figure 4 is a side elevational view of the lower portion of the stand, showing the supporting members in their raised position or out of contact with the floor.

Figure 5 is a similar view showing the supporting members depressed; and

50 Figure 6 is a detail view, partly in section, illustrating the means used for supporting the rock shafts.

Referring to the drawings which illustrate the preferred form of my invention, A designates the legs of the stand which are preferably formed from pieces of metal tubing, B designates rollers or casters arranged at

the lower ends of the legs A, and C designates tubular-shaped supporting members arranged in telescopic relation with the lower end portion of the legs A. It is immaterial, so far as my broad idea is concerned, what type of rollers or casters the legs of the stand are equipped with, but I prefer to provide each leg with a spherical-shaped roller B mounted in a socket 1 provided with a shank 60 2 that projects upwardly into the lower end of the leg, as shown in Figure 2. The supporting members C can be formed in various ways without departing from the spirit of my invention, but I prefer to equip each leg 65 with a supporting member of substantially tubular form whose upper end is of such diameter that it will telescope freely over the lower end portion of the leg and whose lower end portion is of such diameter that it will 70 surround or inclose the socket or bearing of the roller B mounted in the lower end of the leg. The four supporting members C of the stand are combined with an operating mechanism which is adapted to be moved in one 75 direction so as to depress the supporting members C, and thus bodily raise the legs A sufficiently to lift the rollers B from the floor, and moved in the opposite direction 80 so as to lower the legs and raise said supporting members C out of contact with the floor.

In the form of my invention herein illustrated said operating mechanism consists of two horizontally-disposed, transverse rock 90 shafts D and D' arranged at the front and at the rear of the stand adjacent the lower ends of the legs A, rigid arms 3 on said rock shafts connected by means of links 4 to the supporting members C, an operating device, preferably a rigid foot piece 5, on the rock shaft D, and a link 6 that connects the rock shafts D and D' together so as to cause them 95 to move in unison. The arms 3 and links 4 transmit movement from the rock shafts D and D' to the supporting members C, and said arms and links are so proportioned and arranged that when said rock shafts are in one position the supporting members C will 100 be held out of contact with the floor, thus causing the legs of the stand to be supported by the rollers B, as shown in Figure 4. At such times the stand can be moved easily from one place to another, due, of course, to the fact that it is supported by rollers.

When it is desired to hold the stand perfectly rigid and in a stationary position, the

operator places one foot on the operating device 5 and depresses the front end of said device so as to rock the shafts D and D' in such a direction that the arms 3 thereon 5 and the links 4 connected to said arms will force the supporting members C downwardly into engagement with the floor. After said members C have come in contact with the floor further movement of said rock shafts 10 in this direction operates to raise or bodily lift the legs A of the stand, due to the fact that the arms 3 and links 4 form toggles whose lower ends are connected to the members C which bear against the floor and 15 whose upper ends are connected to the legs A of the stand through the instrumentality of the rock shafts D and D'. The link 6 previously referred to is pivotally connected at its opposite ends to brackets 7 on the 20 rock shafts D and D' which are so proportioned that the lower edge of said link will strike against the base portion of the bracket 7 on the rear rock shaft D' when the toggles formed by the arms 3 and links 4 have become straightened, thus limiting the movement of said toggles and causing the operating mechanism for the supporting members C to be locked in its operative position 25 shown in Figure 5.

30 When it is desired to move the stand the operator simply places one foot on the operating device 5 and depresses the heel end of same so as to impart movement to the rock shafts D and D' in a direction to break 35 the toggles formed by the arms 3 and links 4, and thus permit the legs of the stand to move downwardly relatively to the supporting members C.

It is immaterial how the legs A of the 40 stand are braced or connected together, but I prefer to connect the upper end portions of the legs together by two cross pieces 8 arranged at the sides of the stand and two transversely-disposed cross pieces 9 arranged 45 at the front and at the rear of the stand. The lower end portions of the legs are connected together by two cross pieces 8^a arranged at the sides of the stand and the two transversely-disposed rock shafts D and 50 D' previously referred to, said rock shafts being so mounted that they can turn or oscillate on bearings carried by the legs A, as shown in Figure 6. The bearings that support the rock shafts D and D' preferably 55 consist of cylindrical-shaped lugs 10 on plates 11 which are clamped to the legs A by tie rods 12 arranged inside of the rock shafts and provided at their ends with screw-threaded portions which pass through 60 the legs. A tie rod 12 is associated with

each of the rock shafts, as shown in Figure 6, and the opposite ends of said tie rod are threaded so as to receive nuts 13, one of which is arranged at one side of the bearing plate 11 and the other at the side of a 65 co-operating plate 11^a. While I prefer to mount the rock shafts D and D' in the manner above described, I wish it to be understood that it is immaterial, so far as my broad idea is concerned, how said shafts are 70 mounted or combined with the legs A of the stand.

A stand of the above construction is an improvement on the stands now used extensively for supporting calculating machines, 75 because their are no portions at the lower ends of the legs of the stand which form lateral projections over which a person is apt to trip in passing the stand; the stand can be moved easily from one place to another when the supporting members C are raised or out of contact with the floor, and when said supporting members C are depressed and locked they hold the stand perfectly rigid and in a stationary position. 80 The operating mechanism that moves the supporting member C axially of the legs A so as to effect the raising and lowering of the stand can be operated by one foot of the user and still another desirable feature of 85 such a mechanism is that it can be manufactured at a low cost and easily applied to the stand.

Having thus described my invention, what I claim and desire to secure by Letters Patent, is:

1. A stand provided with legs equipped with rollers, a tubular member arranged in telescopic relation with the lower end portion of each leg and adapted to be moved 100 downwardly into engagement with the floor so as to elevate the leg and the roller thereon, a pair of horizontally-disposed rock shafts carried by said legs, rigid arms on said shafts arranged adjacent the ends of 105 same, each of said arms being adapted to co-operate with one of said tubular members, and links that join said arms to their co-operating tubular members.

2. A stand provided with legs equipped 110 with rollers, tubular-shaped members arranged in telescopic relation with the lower end portions of the legs of the stand, a pair of rock shafts carried by said legs and connected together in such a manner that 115 they move in unison, an actuating device on one of said rock shafts, and rigid arms on said rock shafts connected by links to said tubular-shaped members.

HIERO GILLAS TIFFANY.
